RAIL GREASING APPLIANCE

Guy Clement Hurrell, London, England, assignor
to The P. & M. Co. (England) Ltd., London,
England, a British company

Application September 7, 1937, Serial No. 162,813
In Great Britain September 8, 1936

4 Claims. (Cl. 184—3)

This invention relates to rail greasing appliances of the kind adapted to be mounted upon the rail and actuated automatically by the wheels of a passing train so as to force grease from a reservoir on to the face of the rail which it is desired to grease. Such appliances are generally mounted upon the outer rail of the track at a curve for the purpose of greasing the inner face of the outer rail as it is well known that by such grease application economy in engine power consumption and reduction in tyre flange and rail wear is brought about. In such appliances it has already been proposed to employ a bevelled greasing plate for distributing the lubricant over the side face of the rail and the chief object of the invention is to evolve a generally improved form of rail lubricator which will be of simple construction and cheap to manufacture and which can be easily and quickly fitted to the rail to which it is to be applied. A further object of the invention is to provide means whereby the quantity of grease or other lubricant discharged at each operation can be effectively controlled and in which the appliance can be easily adjusted by a relatively unskilled workman to vary the grease output.

Referring to the drawings:

Figure 1 is a front elevation of the grease container without pumps attached.

Figure 2 is a part sectional side elevation of the same.

Figure 3 is a side elevation on an enlarged scale of a pump, and the lug to which it is attached.

Figure 4 is a transverse vertical section of the same.

Figure 5 is a cross section of the means for holding the two portions of the apparatus to the rail, and for transferring the grease from pump to rail face.

Figure 5A is a section through another part of the greasing plate.

In its preferred form the lubricating device comprises a cylindrical grease container 1 having one end closed with a removable cover 2 which forms the abutment for the thrust of a spring 3, the free end of which urges forward the sliding piston 4 which pushes forward the grease G with a light pressure, for instance, a pound or so per square inch, which is sufficient to propel it through the ducts 6 to the outlet or communicating ports 7. These ducts are formed within the substantial lugs or blocks of metal 5 formed upon the closed end of the cylinder 1. These lugs serve for the supporting

and locating of the container 1 on the rail, and they have contact points 8 and 9 which are pulled against the vertical portions of the rail and substantially horizontal contact points 10.

The lugs 5 also serve for the attachment of bolts 11 which pass through the rail web, and hold the grease container to the outside, and the greasing plate to the running face of the rail.

The faces of the lugs in which the ports 7 are formed have smooth and preferably flat ends for the attachment of pumps 12 which preferably are in the form of angular blocks of metal of substantial construction, each of which is fitted with plungers 13, with its axis substantially vertical, and with its head projecting above the top face of the pump body 12. The plunger 13 is provided with a flange or stop 14 to limit its upward movement, and to receive the thrust of spring 15.

The lower extremity 16 generally of much reduced diameter, is a working fit in the hole 17 which constitutes the barrel or cylinder of the pump. This barrel is preferably removable, and the top or a shoulder formed at some part of its length serves as a thrust or support for spring 15. The lower end of hole 17 is preferably provided with a simple ball valve 18 held up by a light spring 19.

In the description pump in the singular is sometimes mentioned, and at other times pumps in the plural, and it is to be understood that one pump may be used effectively, but preferably two are used as shown on the drawings, each pump supplying the grease for approximately half the length of the greasing plate.

The action of the pump is as follows:

When tread of the railway vehicle passes over the top of plunger 13 the latter is pushed downwards, the working end 16 enters hole 17 and is withdrawn by the action of spring 15. A vacuum is created in 17 and grease from the space 20 fills up the hollow formed in 17, at the next stroke grease in 17 is forced past the valve 18 into space 21, thence through holes 22 and 23 45 into channel 24 formed in the lug 5 to which the pump is attached.

As the grease is withdrawn from space 20 it is replenished continuously by fresh material entering inlet port 25 in body of pump 12 through port 7 and duct 6 in the lug from the grease container 1.

The construction of the pump as above described permits of it working without an inlet valve, as the top of plunger 16 is withdrawn

enough to permit of the inflow of grease, and on re-entering closes the cylinder 17 except at the bottom where valve 18 is located.

It is found that by making the discharge holes 22 and 23 sufficiently restricted the valve 18 may be omitted, as grease already discharged will not be drawn back as readily as fresh grease will enter from 20 but that the action of the pump is more positive when the valve as described is used, especially when bubbles or pockets of air are present in the pump.

The pumps 12 are adjustably held against the vertical facings of lugs 5 by one or more bolts 26 passing through slotted holes 27 and within the limit of adjustment, inlet port 25 in pump 12 is always open to duct outlet 7, and delivery hole 23 is open to duct 24 on the main casting 5. The purpose of this adjustment is twofold, firstly, the height by which the external end of plunger 13 extends above the tread of passing wheels, determines the stroke and displacement of the pump, and this is increased by raising the pump 12 and decreased by lowering. It is also found in practice that the rails to which the lubricators are fixed may have their upper surface more or less worn down, and the adjustable feature of the pump permits of the apparatus being fixed to such rails and correctly set without altering the main casting, and particularly the bearing points 10 previously referred to.

While grease leaving holes 22 has been described as being discharged into duct 24 whence it will be conveyed to the greasing plate through means connecting lugs 5 with the said plate, to be later more fully described, as an alternative the grease may be caused to leave the pump body 12 through an outlet for example 28 whence it may be conveyed to a greasing plate by means of a tube passing under or through the rail in any convenient way, which it is not necessary to describe further, and the detailed description of the method of conveying the grease to the place from which it is picked up, will be limited to the preferred method.

The fastening bolts 11 preferably two in number, and one to each lug 5 may pass through a hole in 5 and be screwed into the anchorage strip 29 which is placed against the web of the rail on the running side, but preferably the arrangement is reversed and use is made of a bolt having a somewhat longer head than the ordinary bolts of commerce, and under the hexagon head 30 is formed a circular collar 31.

55 The small diameter part of bolt 11 is passed through the metal bar 29 which is substantially the same length as the greasing plate 32 and through a hole drilled through the neutral axis of the rail, and screwed into a hole 33 tapped in lug 5. This hole is prolonged beyond the end of bolt 11 and forms a cavity into which grease discharged into duct 24 as previously described passes via hole 34 into hole 35 in bolt 11 thence through cross hole or holes 36 into space 37 around collar part 31 of bolt, thence into longitudinal channel 38 and vertical channels 39 into space 40 between top of anchor piece or bar 29 and underside of rail head from whence it passes through a plurality of vertical channels 41 to the 65 face of the rail.

The space 37 mentioned above is caused by making the hole in the greasing plate 32 considerably larger than collar 31 of bolt 11. This difference in diameter permits the greasing plate 75 32 to be adjusted in a vertical direction.

It will be seen that collar 31 is pulled up against anchor bar 29 and the latter is consequently pressed against the rail web, preferably with thin fibrous packing washer 42, this latter provides means of readily adjusting the face of 29 to the line of rail face, and also to prevent grease leaking downwards instead of only in the desired direction, that is upwards through grooves 41.

On the outside of plate 32 is a cover strip 43 which is used to seal effectively holes 37A (Figure 5A) against the escape of grease around bolts or screws 11A which hold plate 32 against anchor plate 29 at positions other than those occupied by bolts 11.

In order to prevent the escape of grease around head 30 of bolt 11 a cap 44 is provided for each bolt, and this cap, when forced against strip 43 by bolt 45, not only prevents escape of grease, but helps to hold plate 32 against plate 29 and the rail face.

It will be seen that by slackening bolts or screws 11A and 45 the greasing plate 32 may be adjusted or removed without disturbing the attachment of the anchor plate 29 and grease cylinder 1 to the rail.

What I claim and desire to secure by Letters Patent of the United States is:

1. An automatic rail lubricator for supplying grease to the rail face comprising a plunger type of grease pump actuated directly by the tread of a vehicle wheel passing over the rail, a grease container having means for its attachment to the rail and carrying said pump, means for supplying grease from said container to said pump under pressure and a greasing plate for distributing grease delivered by said pump over the rail face, said pump being adjustably mounted upon said container to permit of said pump being raised or lowered to increase or decrease its effective stroke and thereby vary the quantity of grease supplied to the rail face and also to compensate for wear of the rail head, said pump being in the form of a self contained unit bolted in position upon a lug associated with said grease container, the pump casing having ports adapted to register with ports in the lug communicating with the grease container, said ports in said lug being larger than said ports in said pump casing to ensure registration in any position into which said pump may be moved for adjustment purposes.

2. An automatic rail lubricator for supplying grease to the rail face comprising a plunger type of grease pump actuated directly by the tread of a vehicle wheel passing over the rail, a grease container having means for its attachment to the rail and carrying said pump, means for supplying grease from said container to said pump under pressure and a greasing plate for distributing grease delivered by said pump over the rail face, said pump being adjustably mounted upon said container to permit of said pump being raised or lowered to increase or decrease its effective stroke and thereby vary the quantity of grease supplied to the rail face and also to compensate for wear of the rail head, said pump being in the form of a self contained unit bolted in position upon a lug associated with said grease container, the pump casing having ports adapted to register with ports in the lug communicating with the grease container, said ports in said lug being larger than said ports in said pump casing to ensure registration in any position into which said pump may be moved for adjustment purposes, said grease container and pump having means for their attachment to the rail adjacent

its outer face, said greasing plate being adapted for location adjacent the inner surface of the rail.

3. An automatic rail lubricator for applying grease to the rail face comprising a lubricant container having means for its attachment to the rail, a plunger type grease pump actuated directly by the wheel tread and comprising a self-contained unit adjustably mounted on the lubricant container external thereto, means for supplying lubricant from said container to the pump under pressure and a greasing plate for distributing lubricant delivered by the pump over the rail face.

4. An automatic rail lubricator for applying

lubricant to the rail face comprising a lubricant container having means for attachment to the rail, a plunger type pump comprising a complete pump unit adjustably mounted on the lubricant container external thereto, means for supplying lubricant from the container to the pump under pressure, a fixed greasing plate for distributing lubricant delivered by the pump over the rail face, and a non-return valve device associated with the pump for segregating the pump from the greasing plate after each supply of lubricant has been delivered thereto.

GUY CLEMENT HURRELL.
